UNITED STATES PATENT OFFICE.

JOSEPH SACHS, OF HARTFORD, CONNECTICUT.

SWITCH-OPERATING DEVICE.

1,265,255.

Specification of Letters Patent.

Patented May 7, 1918.

Application filed September 20, 1915. Serial No. 51,671.

To all whom it may concern:

Be it known that I, JOSEPH SACHS, a citizen of the United States, residing at Hartford, in the county of Hartford and State 5 of Connecticut, have invented certain new and useful Improvements in Switch-Operating Devices, of which the following is a specification.

This invention relates to switch-operating devices, the object of the invention being to provide an article of this character which can be easily and quickly connected with or disconnected from several "connectors" as they are known, and which switch-operating device has means for its rigid, substantial association with one or more of the connectors.

In the drawings accompanying and forming part of the present specification I have 20 shown in detail one of the several convenient forms of embodiment of the invention which will be set forth fully in the following description. I do not restrict myself to this particular disclosure; I may depart there- 25 from in several respects within the scope of the invention defined by the claims following said description.

Referring to said drawings:

Figure 1 is a top plan view of a switch 30 operating device involving the invention.

Fig. 2 is an end view of the device as seen from the right in Fig. 1.

Fig. 3 is an inside face view of the same.

Fig. 4 is a top plan, and,

Fig. 5 an end elevation of a switch 35 equipped with an operating device such as that shown in Figs. 1, 2 and 3.

Fig. 6 is a perspective view of a locker, and,

Fig. 7 is a like view of portion of a connector, part of the switch operating device and one of the lockers shown in position to 40 be interlocked with the connector.

Like characters refer to like parts throughout the several views, which it will be noted are on different scales.

I have in use and have set forth in certain prior applications, for instance those filed May 5, 1915, Serial Nos. 26,022 and 26,023 50 certain switch devices involving several connectors. In conjunction with these or equivalent connectors or switching elements I provide a switch-operating device which is removable so that it can be coupled to or un- 55 coupled from the connectors at will. This is one use to which I can put the present

switch-operating device; that is to say it may be associated with connectors constituting parts of the switches such as I have devised. In Figs. 4 and 5 I have shown such 60 a switch. Said switch comprises the base or supporting body 2 usually made of insulating material, pairs of contacts and connectors for making and breaking connection between the respective pairs of contacts. I have 65 shown three of such connectors the outside connectors 3 being as here shown equipped with fuses, while the intermediate connector 4 is of plain or unfused type. Each of the connectors is shown pivoted as at 5 with a 70 contact 6, being co-operative at its rupturing end with a contact 7. The foregoing is a concise description of a so-called base block element with which my present switch operating device can be advantageously utilized, to produce the complete switch. 75

The switch-operating device comprises a body as 8 preferably made in the form of a handle, so that it can be directly manipulated. This may not be necessary in all 80 cases. This body or handle 8 is preferably made of insulating material such as fiber, and is furnished with suitable means by which it can be connected to the necessary connectors. For instance there may be a pin 85 and socket connection between the body or handle 8 and the connectors. The number of connectors and their type do not concern the invention. Three of the connectors are shown and two of them are fused, and the 90 other plain.

In the present instance the body or handle 8 is shown provided with three inwardly extending pins or plugs 9, generally made of metal. The rupturing ends of the three 95 connectors have sockets as 10 to removably receive the plugs or pins 9. It will be clear that when the body or handle 8 is connected with the three connectors the same can be operated as one or simultaneously. If the 100 handle or body be uncoupled from the connectors, the latter can be individually or independently operated. In Figs. 4 and 5 the plugs 9 are shown as fitted properly in the socket portions 10 of the several connectors, 105 so that when the handle is thus positioned, the connectors can as noted be swung open or closed through the manipulation of the handle which to facilitate its operation may have a grasping or manipulating portion 11. 110

I provide means of a suitable kind for interlocking the handle 8 with the connec-

tors. If there are only two of such connectors, the handle will be preferably interlocked with them both in such manner as to prevent longitudinal movement of the handle or movement thereof transversely of the switch. If there are more than two of the connectors as shown in Figs. 4 and 5, it is not essential that the handle be interlocked with them all, but it should preferably be interlocked with at least two of them, and although and as will hereinafter appear, the handle has such an association with the two fused connectors 3, this is not imperative, although it is desirable.

To lock the handle 8 in operative relation I provide what may be considered as lockers or catch members as 12, each having an attaching portion as 13 and a locking portion as 14. As shown the attaching portions 13 are furnished with inwardly extending flanges 15 which overlie the flattened faces of the enlarged butt portions 16 of the outer plugs or pins 9. As represented these flanges 15 have longitudinal slots 17 to receive fastenings as screws 18 tapped into the enlarged portions 16. By running the screws 18 inward, they bind against the flanges 15 to fasten the lockers or catch members 12 securely in their adjusted positions, the slots when the screws 18 are turned out sufficiently, permitting free movement of the lockers. The locking or operative portions of the lockers 12 consist as shown of projections 19 extending inwardly from the arms 14 of said lockers and adapted to enter slots as 20 in the outer connectors.

In Figs. 1, 2 and 3 the lockers 12 are shown as positioned on the handle, and in their outer or inoperative positions. To mount the handle 8 the following procedure may be adopted: The plugs or pins 9 will be first inserted in the respective socket portions 10 of the three connectors, and if necessary the screws 18 loosened to free the two lockers 12, so that they can be moved inwardly to project the lugs or projections 19 into the appropriate slots or holes 20. When this is done the screws 18 will be operated to cause the heads thereof to bind the flanges 15 solidly against the enlarged butt portions of the two outer pins. When it is desired to

remove the handle from the connectors as may be necessary when the connectors are to serve for testing, then the screws 18 are released and the lockers 12 moved out of engagement with the connectors.

What I claim is:

1. An electric switch comprising a plurality of connectors movable simultaneously to electrically open and close the switch, a handle in the form of a crossbar provided with means for detachably and directly connecting the handle with each of the several connectors, and means for removably locking the handle in place independently of the connection of the handle with the connector. 60

2. A switch comprising a plurality of individual connectors, a handle comprising a crossbar, means associated with said crossbar for directly removably connecting said handle with each of the several connectors, and a locker for holding said handle and connectors in mechanically associated relation, said locker being movable to permit of the disconnection of said handle from said 70 connectors without the separation of the locker from its support.

3. An electric switch comprising a connector movable to electrically open and close the switch, a handle provided with means 80 for its detachable and direct slip connection with the connector, and means for locking the handle to the connector, the handle being applicable to the connector while the locking means is connected to its supporting part. 85

4. An electric switch comprising a plurality of connectors each provided with a socket, a handle comprising a cross bar having pins, each individually mechanically as- 90 sociable with the socket of its respective single connector, a locker adapted for holding the handle in mechanical engagement with all of the several connectors, said locker being held to its support at all times whether the handle is associated with the connectors 95 or disassociated therefrom.

In testimony whereof I affix my signature in presence of two witnesses.

JOSEPH SACHS.
